UNITED STATES PATENT OFFICE

170,163

CARRYING TRAY

Walter H. Randall, Waterville, Maine, assignor to
 Keyes Fibre Company, Portland, Maine, a corporation of Maine

Application November 21, 1952, Serial No. 22,391

Term of patent 14 years

(Cl. D44—10)

To all whom it may concern:

Be it known that I, Walter H. Randall, a citizen of the United States of America, residing at Waterville, county of Kennebec, State of Maine, have invented a new, original, and ornamental Design for a Carrying Tray, of which the following is a specification, reference being had to the accompanying drawing, forming part thereof.

Fig. 1 is a plan view of a carrying tray, showing my new design;

Fig. 2 is an end elevation of the carrying tray of Fig. 1;

Fig. 3 is a side elevation of the carrying tray of Fig. 1; and

Figs. 4 and 5 are sectional views taken along the lines 4—4 and 5—5 respectively of the carrying tray of Fig. 1.

I claim:

The ornamental design for a carrying tray, as shown.

WALTER H. RANDALL.
